UNITED STATES PATENT OFFICE

140,886

DESIGN FOR A FLORAL HOLDER

Joseph R. Wieber, Corona, N. Y.

Application December 18, 1944, Serial No. 116,964

Term of patent 7 years

(Cl. D35—3)

To all whom it may concern:

Be it known that I, Joseph R. Wieber, a citizen of the United States, residing at Corona, in the county of Queens and State of New York, have invented a new, original, and ornamental Design for a Floral Holder, of which the following is a specification, reference being had to the accompanying drawing, forming a part thereof.

I claim:

The ornamental design for a floral holder, as shown.

JOSEPH R. WIEBER.
